TACKING STRIP

James S. Reid, Shaker Heights, Ohio, assignor,
by mesne assignments, to The Standard Prod-
ucts Company, Cleveland, Ohio, a corporation
of Ohio

Application February 28, 1936, Serial No. 66,183

5 Claims. (Cl. 189—40)

This invention relates to improvements in tacking strips such as are used, for example, in the automotive industry for securing upholstery and the like to the metal interior portions 5 of automobile bodies.

The general object of the present invention is the provision of improved tacking strips which are of simple and inexpensive construction so 10 that they can be made and sold at low cost, which are of durable character, and which effectively perform their intended tack-retaining function.

A more specific object of the present invention is the provision of improved tacking strips which materially conserve the material of which 15 they are made, without causing the strips to be so small in cross-section that they are difficult to handle and without causing any decrease in the cross-sectional size of the tack-retaining portions of the strips.

Another more specific object of the present invention is the provision of improved tacking strips having longitudinal cores of tack-retaining material and of appreciable tensile strength 20 embedded therein, said cores enabling such strips to be more rapidly extruded by the use of an extruding device, even though the material of such strips in which such cores are embedded is of little or no tensile strength.

Another more specific object of the present invention is the provision of improved tacking strips having channel-shaped sheet metal holders, said holders being adapted to be welded or otherwise suitably secured to the metal surfaces 25 which are to be covered by upholstery or the like.

Further objects of the present invention, and further features thereof, will be apparent from the following description of several forms of 30 tacking strips embodying the present invention, reference being had to the accompanying drawing in which

Fig. 1 is a perspective view of one form of tacking strip embodying the present invention; 35 Fig. 2 is a perspective view of the tacking strip of Fig. 1 secured in a channel-shaped sheet metal holder; Fig. 3 is a view similar to Fig. 1 but showing another form of tacking strip embodying the present invention; Fig. 4 is a perspective view of another form of tacking strip 40 embodying the present invention, said tacking strip being secured in another form of a channel-shaped sheet metal holder; and Fig. 5 is a perspective view showing one way of directly securing the tacking strip of Fig. 1 to a sheet 45

metal member which is to be covered with upholstery or the like.

One material of which the present improved tacking strips may be made is a rubber compound, so lightened in weight by the use of suitable fillers, such as sawdust, leather dust, rags or the like, that the present strips are not appreciably heavier than the twisted paper tacking strips which have heretofore been used. The rubber compound of which the present tacking 5 strips are made firmly retains all tacks driven into it, so that upholstery or the like may be readily and permanently secured to such strips by means of such tacks, as will be readily understood.

The present improved tacking strips are preferably formed by extruding the aforesaid rubber compound into strips of the desired cross-sectional size and of the desired cross-sectional shape, any suitable extruding device being used 10 for the purpose. The strips as formed are continuous in length and are subsequently cut into pieces of the desired length. As indicated in the accompanying drawing, the tacking strips preferably are of uniform size and shape in cross-section, the strips being generally rectangular, as 15 shown.

In the tacking strip 1 of Fig. 3 and in the tacking strip 2 of Fig. 4 suitable cores are longitudinally embedded in the rubber compound 20 thereof, along the longitudinal center lines of the strips, the core 3 of strip 1 being located adjacent the bottom thereof and the core 4 of strip 2 being located adjacent the top thereof. The material of which these cores are made is 25 one which not only has tack-retaining properties but which also has a considerably greater tensile strength than the rubber compound in which the cores are embedded, such as paper. The latter property of such cores enabling the 30 tacking strips 1 and 2 to be drawn through the extruding device, and thus formed, at a much greater speed than would otherwise be possible, such drawing speed being determined largely by the tensile strength of such cores.

In order to reduce the amount of the rubber compound necessary for the formation of the present tacking strips and to also reduce the weight thereof, without decreasing in any way the efficiency of the strips, the base and sides of 35 each such strip are longitudinally grooved or recessed intermediate the generally rounded longitudinal corner portions thereof, the base groove or recess 6 of each strip being a relatively wide one and the side grooves or recesses 7 of each 40

strip, there being one such groove or recess 7 in each strip side, being relatively narrow. The top face of each strip, along the longitudinal center line of which the tacks are driven, is generally flat, as shown. The longitudinal corner portions of each strip are not disturbed by the grooving or recessing of the base and sides thereof, so that the strip not only is as sturdy as it otherwise would be but also, the strip still 10 contains all of that material which is necessary and desirable for tack-receiving and tack-retaining purposes.

The amount of rubber compound necessary for the formation of the present tacking strips also 15 may be reduced, without disturbing the efficiency of the strips, by providing the strips with suitable openings 10 extending longitudinally therethrough, and each of the strips here shown is provided with a pair of such openings. As shown, 20 the openings 10 of the tacking strip 12 of Fig. 1, of the tacking strip 13 of Fig. 2, of the tacking strip 1 of Fig. 3 and of the tacking strip 14 of Fig. 5 are of circular shape, and the openings 10 of the tacking strip 2 of Fig. 4 are of generally 25 triangular shape. The two openings of each of the present strips lie in the same cross plane and are spaced apart a sufficient distance to permit tacks to be driven into that portion of the strip lying therebetween. In the tacking strip 30 1 of Fig. 3, the openings 10 are arranged in a plane above that of the core 3 and in the tacking strip 2 of Fig. 4, the openings 10 are arranged in a plane below that of the core 4.

The grooves or recesses 6 and 7 of the tacking 35 strips and the openings 10 thereof may be readily formed in the strips during their extrusion by an extruding device, the shape of the die opening of the extruding device determining, of course, the cross-sectional shape of the tacking strips, 40 as will be readily understood.

To secure the present tacking strips to metal surfaces which are to be covered with upholstery or the like, channel-shaped sheet metal holders may be utilized, such as the holder 16 of 45 Fig. 2 or the holder 17 of Fig. 4. The tacking strip 13 of Fig. 2 is secured within the holder 16 by the inwardly bent upper edge portion 16a of the side walls of such holder, said side wall edge portions firmly engaging the longitudinal edge portions 50 of the tack-receiving top face of said tacking strip. The tacking strip 2 of Fig. 4 is provided, within the grooved or recessed portions of its sides, with outwardly extending longitudinal ribs 55 20, one at each side, and such tacking strip is secured within the holder 17 by the inwardly bent upper edge portion 17a of the side walls of such holder. As shown, the side walls of the holder 17 are of lesser depth than the side walls of the 60 holder 16, so that the inwardly extending side wall edge portions 17a of the holder 17 lie just above and in engagement with the side ribs 20 of such tacking strip 2. The metal holders 16 and 17, with tacking strips secured therein, may 65 be easily and conveniently secured, by spot-welding or the like, to any metal surfaces which are to be covered with upholstery or the like.

Another method of securing the present tacking strips to metal surfaces is to provide such 70 surfaces with suitable clamping tongues, such as the tongues 22 of Fig. 5. As here shown, two sets of tongues 22 are struck up from the metal member 23, for clamping engagement with both sides of the tacking strip 14, the side grooves or recesses 10 of such strip enabling said tongues to

be bent down over the lower longitudinal corner portions of such strip.

Other features of the present invention will readily occur to those skilled in the art to which this invention relates, and various changes may 5 be made in the tacking strips here illustrated without departing from either the spirit or the scope of this invention.

What I claim is:

1. A tack strip formed of tack-retaining composition and being of uniform generally rectangular cross section throughout its length, thereby forming top, bottom and side surfaces, the top of said strip being substantially flat to form a tack-receiving surface, the sides of said strip 15 between the bottom and top portions having longitudinally extending grooves to provide generally rounded corners between the sides and the top of said strip, and the bottom having a longitudinal groove which extends upwardly from the bottom corner portions forming a substantially concave bottom surface and generally rounded corners between the bottom and side surfaces, the grooves in the sides being relatively narrow with respect to the groove in the bottom and being located at such a distance below the top that they do not weaken the upper portion of the strip in which the thicker portions of the tacks are embedded, and the depth of said strip being such that tacks driven through the upper portion of 30 said strip do not extend into the lower groove.

2. A tack strip formed of tack-retaining composition and being of uniform generally rectangular cross section throughout its length, thereby forming top, bottom and side surfaces, the top 35 of said strip being substantially flat to form a tack-receiving surface, the sides of said strip between the bottom and top portions having longitudinally extending grooves to provide generally rounded corners between the sides and top portion; and the bottom portion being longitudinally grooved to provide rounded corners between the bottom and the side portions, the grooves in the side portions being relatively narrow with respect to the grooves in the bottom portion, said strip 40 also having a plurality of openings located on opposite sides of a plane passing through the longitudinal axis and the upper and lower portion of said strip midway between the sides, said openings and the side grooves being located at such 45 a distance below the top that they do not weaken the upper portion of the strip in which the thicker portions of the tacks are embedded, and said openings being spaced a sufficient distance apart 50 to permit tacks to be driven from the top portion 55 into the composition between the openings.

3. A tack strip formed of tack-retaining composition and being of uniform generally rectangular cross section throughout its length, thereby forming top, bottom and side surfaces, 60 the top of said strip being substantially flat to form a tack-receiving portion, the sides of said strip between the bottom and top portion having longitudinally extending grooves to provide generally rounded corners between the sides and top 65 portion, and the lower portion being longitudinally grooved from its corner portions to provide rounded corners between the bottom and side portions and a substantially concave bottom portion, the grooves in the side portions being relatively narrow with respect to the grooves in the bottom portion, said strip having a pair of openings located on opposite sides of a longitudinal plane passing through the axis and the upper and bottom portion of said strip midway between the 70 75

sides and being located a sufficient distance from each other to permit tacks to be driven from the top into the composition between them, said openings and the side grooves being located at such a distance below the top portion that they do not weaken the upper portion of said strip.

4. A tack strip formed of tack-retaining composition and being of uniform generally rectangular cross section throughout its length, thereby forming top, bottom and side surfaces, the top of said strip being substantially flat to receive tacks, the sides of said strip between the bottom and top portions being provided with longitudinally extending grooves to form generally rounded corners between the sides and top portion and the bottom portion having a longitudinally extending groove forming rounded corners between the bottom and side portions, the grooves in the side portions being relatively narrow with respect to the grooves in the bottom portion and their apex being located below a longitudinal plane extending through the axis midway between the bottom and top portions, said strip having openings therein located on opposite sides of a longitudinal plane passing through the axis and the top and bottom of said strip midway between said sides and at such a distance below the upper portion of said strip in which the thick portions of the tacks are embedded that they do not weaken the up-

per portion of said strip, said opening being spaced from each other a sufficient distance to permit tacks to be retained in the composition between them.

5. A tack strip formed of tack retaining composition and being of uniform generally rectangular cross section throughout its length, thereby forming top, bottom and side surfaces, said strip comprising a substantially flat upper portion to receive tacks, the sides of said strip between the bottom and top portions being provided with longitudinally extending grooves to form generally rounded corners between the sides and top portion and the bottom portion having a longitudinally extending groove forming rounded corners between the bottom and side portions, the grooves in the side portions being relatively narrow with respect to the grooves in the bottom portion, said strip having a pair of openings therein, the openings being located on opposite sides of a longitudinal plane passing through the axis and the top and bottom of said strip midway between said sides and below a longitudinal plane extending through the axis and sides midway between the top and bottom and being spaced at a sufficient distance from each other to permit tacks to be retained in the composition between them. 25
